UNITED STATES PATENT OFFICE.

EDWARD M. SHINKLE, OF THE UNITED STATES ARMY.

BULLET.

1,187,867.

Specification of Letters Patent. Patented June 20, 1916.

Application filed February 19, 1915. Serial No. 9,399.

To all whom it may concern:

Be it known that I, EDWARD M. SHINKLE, major U. S. Army, a citizen of the United States, residing at Philadelphia, in the 5 county of Philadelphia and State of Pennsylvania, have invented certain new and useful Improvements in Bullets; and I do hereby declare the following to be a full, clear, and exact description of the invention, such as will enable others skilled in the art to which it appertains to make and use the same.

This invention relates to bullets for fire arms of all kinds, and has for its object 15 to improve the bullet made the subject of U. S. Patent to J. E. Bell, #807,012, December 12, 1905 for rifle bullet.

With this object in view the invention consists in the novel details of construction 20 and combinations of parts more fully hereinafter disclosed and particularly pointed out in the claims.

Referring to the accompanying drawings forming a part of this specification in 25 which like numerals designate like parts in all the views:—Figure 1 is a diagrammatic view partly in section of a bullet made in accordance with my invention; Fig. 2 is a sectional view on a greatly exaggerated scale of some of the parts shown 30 in Fig. 1; and Fig. 3 is a view similar to Fig. 1 showing the old style bullet illustrated in U. S. Patent #807,012, above mentioned.

35 The bullets used in military and other high velocity rifles are either composite bullets consisting of a jacket of copper, cupronickel, soft steel, or other metal of considerable strength, filled with a softer and 40 more ductile metal such as lead or one of its alloys, or they are made of a single metal or alloy such as copper or bronze. In either case the most customary form is a cylindrical body of a diameter approximately 45 equal to the bore of the rifle measured to the bottom of the grooves, to which is added a point, that may be conical, ogival, or of any other form suitable for the purpose for which the bullet is designed.

50 The fact that the diameter of the bore of the rifle is approximately 0.008" less when measured to the lands than when measured to the bottom of the grooves of the rifling causes the rifling to cut grooves in a manner 55 well known in the exterior of the body of the bullet for the entire length over which

its diameter is greater than the nominal bore or the diameter measured to the lands. While it is necessary to have some portion of the body of a diameter approximately 60 as great as the diameter of the bore of the rifle measured to the bottom of the grooves, the length of the portion of this diameter need only be enough to impart angular velocity to the bullet and to prevent the escape 65 of powder gases past the bullet. Any greater length of this diameter simply requires a greater length of metal to be cut by the lands of the rifling and thus increases the friction in the bore. 70

Inventors and experimenters with small arms rifle bullets have recognized the loss of efficiency of bullets of the cylindrical body type and have attempted in various ways such as by the use of cannelures filled 75 with a lubricant, and the use of a bullet the main portion of the body of which is cylindrical and of the nominal diameter of the rifle, with a short cylindrical portion at the rear of greater diameter, to reduce 80 the friction in the barrel. One example of such bullets is found in the said U. S. Patent 807,012. But such a bullet has very serious defects as have all others known to me which will be apparent when it is remembered that: In the first place if a bullet of this character is entered into the mouth of the cartridge case far enough to afford a reasonable security in handling, the front of the rotating band will not come 85 in contact with the real conical portion of the rifling usually known as the "forcing cone." The result is that the bullet must move in a distance of say 0.25" more or less, before taking the rifling. This is detrimental to accuracy, and in addition allows the escape of a portion of the powder gases past 90 the opening between the bullet and the forcing cone causing excessive erosion and loss of effective work of a portion of the gases 95 from the powder charge. Again that type of bullet having a cylindrical body of the same diameter throughout first comes in contact with the forcing cone or conical portion of the rifling at a point on the bullet 100 forward of the cylindrical body. Under these conditions gas escapes past the bullet before it has moved forward far enough to completely seal the bore. 105

To remedy the objections described above 110 my bullet is so designed as to substantially or completely seal the bore when forced

into firing position by the breech mechanism and has as small an amount of metal to be cut by the lands of the rifle as will be sufficient to seal the bore against the escape of powder gases as well as to impart an angular velocity to the bullet. A suitable length for the metal to be cut along the length of the bullet in many cases will be say 0.1664".

In order that the present invention may 16 be clearly understood, reference is had to the drawings in which—

1 indicates the barrel of any rifle, pistol, or fire arm provided with rifling; 2 the lands of the rifling, 3 the point near the rear 15 end of the lands where the said lands begin to taper off to form a forcing cone, 4 the tapered or beveled surface of the lands, or forcing cone, 5 the extreme rear end of the lands or base of said forcing cone, and 6 the 20 wall of the cartridge receiving chamber.

7 represents the cartridge casing, 8 the rear end of the bullet fitting said casing, 9 the body of the bullet, and 10 its forward tapered end.

25 The above features of construction are or may be of any well known or suitable dimensions.

In the bullet 11, made the subject of the said U. S. Patent 807012, its rear end 12, 30 was made the full diameter of the bullet then in use, while its forward body portion was slightly reduced in size to fit the diameter of the bore between the lands all as is illustrated in Fig. 3. I have discovered, 35 however, as above stated, that whereas the bullet of said patent did constitute an improvement over the prior bullets, yet in practice it is defective in the following particulars: The said full sized rear end 12 40 joins the reduced fore body 11 of the bullet by a rather abrupt shoulder 13, so that since the said end 12 does not normally enter the forcing cone 4, there is left a hollow space 14, between the wall of the forcing cone and 45 the shoulder 13. In other words, although I found in actual tests that the bullet of said patent did reduce the friction in the gun, and therefore produced a higher velocity for a given pressure, all as disclosed in said 50 patent, yet, said tests further showed that these results were not satisfactory, in that the bullet of the patent is not accurate and did not otherwise function as efficiently as was desired. I further discovered from said 55 tests that these defects were due to the presence of the space 14 between the rear end 12 and reduced fore body 11 of the bullet, which permits the gases of explosion to escape to a greater or less extent before the 60 rear end 12 has fully taken the rifling. In the present invention I remedy these defects as also stated above by doing away with the abrupt shoulder 13 altogether, and while retaining a reduced fore body 9, I so taper 65 that portion 15 of the bullet that is to take

the rifling that its surface 16 will fit, or substantially fit, the surface 4 of the particular forcing cone with which it is to function, all as will be clear from Figs. 1 and 2.

The rear end 8 of my bullet of course may 70 be of various shapes and dimensions to suit the arm it is designed for, but in the drawings I have illustrated it as cylindrical, and of the same diameter as the body 9.

In order to give a specific example of the 75 construction of a bullet made in accordance with this invention, it is said: The bullet shown in Figs. 1 and 2 of the drawing which is not to scale is designed for use in the United States magazine rifle caliber .30, 80 model of 1903, chambered for model of 1906 ammunition, and is intended to illustrate the principles involved so clearly that anyone skilled in the manufacture of small arms ammunition may be able to manufacture 85 ammunition of this design for any other fire arm by making suitable changes in dimensions.

The cylindrical base portion 8 of this bullet is of a diameter of substantially 90 0.2995", which is equal to or slightly greater than the nominal diameter of the rifle in which it is to be fired. The conical section 15 fits the forcing cone 4 of the rifle in which it is to be fired. The cylindrical portion 9 95 is equal to or slightly greater in diameter than the nominal bore of the rifle in which it is to be fired, and extends from the conical portion 15 to the beginning of the curvature of the pointed end 10, which can be of any 100 shape desired. A cannelure 20 may or may not be added as desired, at the front end of the part 8 for crimping purposes.

It is obvious that those skilled in the art 105 may vary the details of construction, as well as the arrangement of parts without departing from the spirit of my invention—for example, the dimensions appearing on the drawings may be increased say 0.001"—and therefore I do not wish to be limited to the 110 above disclosure except as may be required by the claims.

What I claim is:—

1. A bullet for use in military rifles provided with a sharp nose portion; a cylindrical portion of substantially the diameter of the bore between the lands located in rear of and joining said sharp nose portion; a forwardly tapered portion located in the rear of and joining said cylindrical portion; 115 said tapered portion having a diameter at its front end of substantially the diameter between the lands, and having a diameter at its rear end of substantially the diameter of the bore between the grooves; and a second 120 cylindrical portion in rear of and joining said tapered portion substantially as described.

2. A bullet for use in military rifles provided with a sharp nose portion, a cylindri- 125

cal portion of the diameter of the bore between the lands located in rear of and joining said sharp nose portion; a forwardly tapered portion having a base of the 5 diameter of the bore between the grooves in rear of and joining said cylindrical portion; and a second cylindrical portion of the same diameter as said first named cylindrical por-

tion provided with a groove in rear of said tapered portion, substantially as described. 10

In testimony whereof I affix my signature, in presence of two witnesses.

EDWARD M. SHINKLE.
